PLATE DRIER

Filed Dec. 8, 1928

F. T. Powers

INVENTOR

UNITED STATES PATENT OFFICE

FRANK T. POWERS, OF DOUGLASTON, NEW YORK

PLATE DRIER

Application filed December 8, 1928. Serial No. 324,782.

My invention relates to improvements in apparatus for use in the removal of surplus water from the surface and for the drying out of the plates of metal or glass used in the preparation of photo-engraved printing plates commonly used in the photo-mechanical printing process, known as "half-tones" and "line cuts."

In certain stages of the process of preparation of photo-mechanical printing plates they are subjected to a washing process which consists either of flowing water over their surfaces or of immersing the plates in the water, preferably the former, and thereafter the surface of the plate is dried by any one of several processes. These drying processes commonly consist of applying an absorbent material to the surface of the plate to absorb and remove the water. With this process great care must be exercised to avoid injury to the plate and at the same time to completely remove the last drop of water from the surface. The object of this invention is to provide a means of removing the water from plates without the danger of injury to the plates and to accomplish the removal of the fluid in a minimum of time and in a thorough manner.

I have found that a multiplicity of small jets of compressed air so arranged and directed that they impinge on the wet surface of the plate is a very effective and rapid method of drying these plates, and I have embodied this invention in an apparatus of the type shown in the accompanying figures. Be it understood that there are many and various forms of apparatus other than that indicated in the figures which will serve as a suitable means of reducing my invention to practice, but the form shown is a preferred embodiment of my invention. Other forms or variations of this form will be obvious to those skilled in the art.

In the accompanying drawing like numbers indicate the same or similar parts.

The apparatus, one form of which is shown by way of example in the drawing, consists of a suitable hollow chamber, 1, preferably of metal, having a series of perforations, 1a,

in its under side. This chamber is carried on trunnions, 2, arranged to rotate in bearings, carried by the brackets, 3. Through one of these trunnions, which is of a hollow or tubular form, compressed air may be delivered to the chamber by means of a pipe, 3a, from a storage tank, 4. This tank is kept filled with compressed air at a suitable predetermined pressure by any available means such as an air compressor, 5. Beneath the chamber, 1, is provided a table, 6, upon the top of which the plate to be dried is placed. For the more convenient placing of the plate in position on the table the chamber, 1, may be lifted by rotating it upon its trunnions, 2, and to fix the position of the chamber, 1, at the proper distance from the plate the said chamber is provided with legs or distance members, 7, by means of which the chamber, when lowered over the plate, will always come to rest at the proper height above the plate.

I have found that for best results it is important that the air nozzles or outlets in the chamber, 1, be spaced between one and two inches apart in each direction and that with a given pressure of air in the chamber the height of the under side of the chamber above the plate should be constant.

The method of operation is as follows:

The chamber, 1, having been lifted to a vertical position by rotating it about the trunnions, 2, the plate to be dried is placed face upward upon the table, 6. The chamber is then lowered to a horizontal position with the legs, 7, resting on the table. The compressed air in tank, 4, which has previously been stored up by the operation of the compressor, 5, is now released by the opening of the valve, 3b, in pipe 3a, and admitting the air to the chamber, 1. This high pressure air issuing at high velocity through the nozzles, 1a, impinges on the plate and almost instantly removes all surplus water from the surface of the plate. Valve 3b is then closed and compressor 5 then stores a fresh supply of compressed air in tank 4 in readiness for instant use when the next plate is ready for drying.

Having described my invention and one

form of apparatus in which it may be utilized, I now state what I claim to be novel and for which I desire to secure Letters Patent:

1. The method of drying photo mechanical printing plates, which consists of simultaneously impinging air at high velocity upon the entire surface of one side of the plate, whereby the moisture thereon is substantially instantaneously dislodged and mechanically removed.
2. The method of drying photo mechanical printing plates, which consists of simultaneously impinging air at high velocity through a multiplicity of points, simultaneously against the entire surface of one side of the plate, to mechanically remove the moisture therefrom.
3. In an apparatus for drying photo mechanical printing plates, the combination of a rigid support for holding the plate in a stationary position, a movable chamber having a multiplicity of closely spaced apertures positionable in relation to the plate, and means for suddenly supplying air at high pressure and in large volume to said chamber and through said apertures to dislodge and mechanically remove the moisture from the surface of the plate.
4. In an apparatus for drying photo mechanical printing plates, the combination of rigid support for holding the plate in a stationary position, a movable chamber having a multiplicity of closely spaced apertures, positionable in relation to the plate, a storage receiver for air at high pressure, a communicating duct between said chamber and said receiver, and quick operating means for suddenly opening and closing said duct, substantially as described.

40 Signed at Douglaston, in the county of Queens, city and State of New York, this 5 day of Dec. A. D. 1928.

FRANK T. POWERS.
